HEAT EXCHANGER

Joseph Price, West New Brighton, N. Y., assignor
to The Griscom-Russell Company, New York,
N. Y., a corporation of Delaware

Application February 19, 1936, Serial No. 64,631

11 Claims. (Cl. 257—236)

This invention relates to heat exchangers and more particularly to improvements in heat exchangers of the type in which a pair of tube sheets or headers are interconnected by a bundle of flexible tubes which, at least during normal operation of the apparatus, are bowed or laterally displaced. Heat exchangers of this type comprise one or more groups of bowed tubes, arched or bowed in one direction. If the headers or tube sheets are rigidly secured in spaced relation to each other, the expansion and contraction of the tubes with changes in temperature produce a flexure of the tubes; contraction of the tubes tends to straighten them out and expansion of the tubes tends to increase the bow or lateral displacement thereof. This flexure of the tubes effectively removes any scale deposited on the tube surfaces.

It has been found that if the bundle of bowed tubes is of considerable length some of the tubes may in the course of time become warped, or they may expand or contract more than other tubes, with the result that the group of tubes are no longer properly spaced from each other. This is particularly true with respect to bowed tube heat exchangers in which the tubes are normally arched or bowed upwardly, for in apparatus of this particular type some of the tubes may sag more than others and after extended use the major portion of the tube bundle may be out of alignment. It has been noted for example that in bowed tube heat exchangers in which 1" O. D. Admiralty tubing is employed, some of the tubes sag down out of their vertically bowed position where the length of the tube bundle exceeds approximately fifteen or sixteen feet.

An object of this invention is to provide means for restricting or limiting the movement of the tubes of a bowed tube heat exchanger, in the direction opposite to that in which the tubes are normally bowed. My invention thus makes it possible to use long tube bundles without the danger of having the tubes sag or otherwise become displaced out of their normally bowed positions. A further object of the invention is to provide means for thus restraining the movement of the tubes without interfering with the free movement of the tubes in the direction in which they are bowed. One embodiment of the invention comprises a series of supporting bars for engaging the tube bundles at points remote from the ends thereof and from the center of the tube bundle and these bars are preferably rigidly mounted in such a way that they

do not interfere with the normal movement of the tubes during expansion and contraction thereof but limit or restrict abnormal displacement of the tubes out of alignment or proper spaced relation to each other. I may also provide means for preventing any substantial lateral movement of the tubes at right angles to the planes in which they are normally bowed.

My improved tube supporting apparatus may be mounted in a frame connected to the headers so that the headers, the tube bundle and the supporting means constitute a unitary structure.

The tube supporting elements for preventing abnormal displacement of the tubes preferably comprise a plurality of flat bars inclined at an angle corresponding with the inclination of those portions of the tubes adapted to be engaged by these bars, and the bars are preferably mounted on supports which extend parallel to the tube sheets or headers. The bars are preferably threaded onto these supports and mounted in spaced relation to each other by spacers threaded onto the supports. The bars and spacers may engage each other in such a manner that the bars are inclined at an acute angle to the axes of the bar supports. This may be accomplished in various ways but I prefer to provide the bars with spacer-engaging surfaces extending at such an angle with respect to the tube-engaging surfaces of the bars that these tube-engaging surfaces are parallel to the portions of the tubes engaged thereby when the bars are firmly secured in spaced relation to each other on the bar supports.

The various objects and advantages of my invention will be more apparent upon considering the following detailed description of one embodiment of the invention as applied to an evaporator, this embodiment of the invention being illustrated in the accompanying drawings in which:

Fig. 1 is a vertical sectional view of a bowed tube evaporator showing a typical application of my invention;

Fig. 2 is an enlarged transverse sectional view, taken on line 2—2 of Fig. 1;

Fig. 3 is an enlarged sectional view of a portion of the apparatus shown in Figs. 1 and 2;

Fig. 4 is a transverse sectional view, taken on line 4—4 of Fig. 1 and

Fig. 5 is a fragmentary enlarged sectional view, taken on line 5—5 of Fig. 1.

The accompanying drawings illustrate a heat exchanger suitable for use as an evaporator,

and for other purposes, the apparatus comprising a shell 1 having a liquid inlet 2 and a vapor outlet 3. The shell is provided with a removable cap 4 and the shell encloses a heat exchanger unit having an inlet 5 and an outlet 6. The heat exchanger unit comprises headers 7 and 8 interconnected by a bundle of bowed tubes 9. The ends of these tubes are expanded into openings in the headers or otherwise firmly secured thereto.

In Fig. 1 the flexible tubes 9 of Admiralty metal, or the like, are bowed upwardly. The tube bundle comprises vertically arranged rows of tubes bowed upwardly and the tubes are so arranged that the bundle may also be considered as comprising horizontal rows of tubes.

A frame extending between the headers 7 and 8 comprises transverse members 10, 11, 12 and 13, the ends of these transverse members being secured to the longitudinal frame members 14, 15, 16 and 17. The headers 7 and 8 are held in fixed spaced relation to each other by means of tie rods 10', 11', 12' and 13', which clamp the headers to the frame.

The headers 7 and 8 may be spaced a considerable distance apart to accommodate a relatively long tube bundle, and my invention contemplates providing means for insuring that all of the tubes of the tube bundle are properly positioned with respect to each other. With this object in view I have provided supports for the horizontal rows of tubes, these supports being shown at 18 and 19. Each of these supports comprises bottom and top crosspieces 20 and 21 and a pair of screw threaded side rods 22 and 23 (see Fig. 2). These rods have threaded thereon a series of supporting bars 25 with short sleeves or spacers 24, interposed between them. These bars 25 are preferably inclined at an angle so that the upper surfaces thereof are parallel with the lower surfaces of the tubes at the point where the bars engage the tubes. Portions of the supporting bars 24 may be cut away to provide spacer-engaging surfaces 26 (see Fig. 3) that extend horizontally and therefore parallel with the ends of the spacers. When the nuts 27 on the rods 22 and 23 are tightened to clamp the supporting bars 25 firmly against the spacers, the supporting bars 25 are securely held in place with their tube engaging surfaces parallel to those portions of the tubes engaged thereby. In this manner a rigid stationary support is provided for each horizontal row of tubes. With the transverse members 20 and 21 welded or otherwise permanently secured to the frame members 14, 15, 16 and 17, the tube supports 18 and 19 are firmly mounted on the frame, which is secured to the headers 7 and 8.

Referring to Fig. 1, it will be noted that the tube supports 18 and 19 are located at points remote from the ends of the tube bundle, and remote from the center of the tube bundle. These supports can be located in such a way that the center span of the tube bundle between these supports is not excessive in length. By using such supports the tubes are prevented from sagging beyond a certain point. It will be understood that temperature changes cause elongation or contraction of the tubes, and, with the headers held in fixed spaced relation to each other, the tubes are flexed whenever these temperature changes occur. Elongation of the tubes increases the bowing or arching of the tubes upward, and, when the temperature of the tubes is lowered, they contract and tend to straighten out. The

supports 18 and 19, however, prevent the tubes from sagging to an undesirable extent.

I may also provide means for maintaining the tubes in proper vertical alignment. In the accompanying drawings I have illustrated for this purpose three cages 28, 29 and 30, the cage 30 being shown in detail in Fig. 4. Each of these cages comprises a series of vertically arranged bars 31 secured to a crosspiece 32 at the bottom. The outer bars 31' may be welded or otherwise permanently secured to the frame members 14 and 15 and they may be secured to or integral with a top crosspiece 33 which is secured to the upper frame bars 16 and 17. The upper ends of the bars 31 may be secured to the top crosspiece, although it may be convenient to secure some of these bars directly to the upper frame members 16 and 17, as illustrated at 34 and 35 in Fig. 4. The bars 31 are located between the vertically arranged rows of tubes 9 and serve to prevent the tubes from becoming displaced laterally. If desired, diagonal crosspieces 36, 37, 38 and 39 may be employed as best illustrated in Fig. 1. By using some means such as the cages 28, 29 and 30 for preventing lateral displacement of the tubes, and by employing the supports 18 and 19, the flexible tubes are maintained in proper spaced relation to each other. The tubes are free to arch upwardly away from the supporting bars 25 but their lateral movement is restricted by the cages 28, 29 and 30 and the bars 25 prevent the tubes from sagging to an undesirable extent.

In the evaporator illustrated in the accompanying drawings the liquid to be evaporated is supplied to the shell 1 through the fluid connection 2 and the vapors are discharged through the fluid connection 3. The heating medium is supplied to the heat exchanger unit within the shell this medium entering through fluid connection 5 from which it passes through suitable connections 40 and 41 to a supply pipe 42 extending lengthwise of the heat exchanger unit to the header 7. From this header 7 the heating medium passes through the bundle of tubes to the header 8 and it is then discharged through the connections 43 and 44 and the fluid connection 6. The heat exchanger unit rests on a track mounted in the lower portion of the shell this track comprising longitudinally extending rails 45 resting on transverse members 46 which may be secured to the shell.

While I have illustrated one typical application of my invention as applied to an evaporator it is to be understood that the use of my improvements is not confined to any specific type of apparatus but may be employed generally in the heat exchanger art. My invention is therefore not limited to the particular details of construction illustrated and described but includes such modifications thereof as fall within the scope of the appended claims.

1. Apparatus of the type described comprising a pair of headers, means for holding said headers in fixed spaced relation to each other, a plurality of rows of flexible tubes interconnecting said headers, said rows of tubes being bowed in one direction, and a plurality of stationary bars for separately engaging each of said rows of tubes to restrict movement thereof in the opposite direction.

2. Apparatus of the type described comprising a pair of headers, means for holding said headers in fixed spaced relation to each other, a plurality of rows of flexible tubes interconnecting said

headers, said rows of tubes being bowed in one direction, and a plurality of stationary bars for separately engaging each of said rows of tubes to restrict movement thereof in the opposite direction, the said tubes being free to move away from said bars in the direction in which they are bowed.

3. Apparatus of the type described comprising a pair of headers, means for holding said headers in fixed spaced relation to each other, a bundle of flexible tubes interconnecting said headers, said tubes being bowed in one direction in parallel planes, means for preventing lateral movement of said tubes at right angles to said planes and stationary means for restricting movement of said tubes in the opposite direction in said planes.

4. Apparatus of the type described comprising a pair of headers, a frame secured to said headers, a bundle of flexible tubes interconnecting said headers, said tubes being bowed in one direction in parallel planes, means carried by said frame for preventing lateral movement of said tubes at right angles to said planes, and means fixed with respect to said frame for restricting movement of said tubes in the opposite direction in said planes.

5. Apparatus of the type described comprising a pair of headers, a bundle of flexible tubes interconnecting said headers, said tubes being bowed in one direction, supporting means for restricting movement of said bowed tubes in the opposite direction, said supporting means comprising a plurality of flat bars for engaging said tubes at a point remote from the ends thereof and from the center thereof, said bars being disposed parallel to those portions of the tubes engaged thereby.

6. In apparatus of the type described, a tube support for a plurality of rows of bowed tubes, comprising a pair of rods, a plurality of supporting bars one for each row of tubes, said bars being threaded onto said rods, and means for securing said bars to said rods in fixed spaced relation to each other.

7. In apparatus of the type described, a tube support for a plurality of rows of bowed tubes, comprising a pair of rods, a plurality of supporting bars one for each row of tubes, said bars being threaded onto said rods, and means including spacers on said rods between said bars

for securing said bars to said rods in fixed spaced relation to each other.

8. In apparatus of the type described, a tube support for a plurality of rows of bowed tubes, comprising a pair of rods, a plurality of flat supporting bars one for each row of tubes, said bars being threaded onto said rods, and means including spacers on said rods between said bars, for securing said bars to said rods in fixed spaced relation to each other, said spacers and bars engaging each other so that the plane of each bar extends at an acute angle to the axis of one of said rods.

9. Apparatus of the type described comprising a pair of headers, a bundle of flexible tubes interconnecting said headers, said tubes being bowed in one direction whereby portions thereof between one of the headers and the center of the tube bundle extend at an obtuse angle to said header, and a plurality of stationary flat bars having tube-engaging surfaces for engaging said portions of the tubes, said surfaces being substantially parallel to said portions of the tubes.

10. Apparatus of the type described comprising a pair of headers, a bundle of flexible tubes interconnecting said headers, said tubes being bowed in one direction whereby portions thereof between one of the headers and the center of the tube bundle extend at an obtuse angle to said header, a plurality of stationary flat bars having tube-engaging surfaces for engaging said portions of the tubes, supports for said bars extending parallel to said header, and spacers on said bars, said spacers having surfaces at right angles to said supports for engaging said bars, and said bars having spacer-engaging surfaces extending at an angle to the tube-engaging surfaces of said bars.

11. Apparatus of the type described comprising a pair of headers, a plurality of flexible tubes interconnecting said headers, said tubes being bowed in one direction, means for holding said headers in fixed spaced relation to each other, and stationary supporting means having surfaces for engaging the tubes for restricting movement of said tubes in the opposite direction, the said tubes being free to move away from said surfaces in the direction in which the tubes are bowed.

JOSEPH PRICE.
